UNITED STATES PATENT OFFICE.

DOUGLAS S. CAMPBELL, OF CLEVELAND, OHIO.

DESIGN FOR AN ADVERTISING SIGN.

Application filed January 15, 1926. Serial No. 16,100. Term of patent 14 years.

To all whom it may concern:

Be it known that I, DOUGLAS S. CAMPBELL, a citizen of the United States, residing at Cleveland, in the county of Cuyahoga and State of Ohio, have invented a new, original, and ornamental Design for an Advertising Sign, of which the following is a specification, reference being had to the accompanying drawing, forming part thereof.

Figure 1 is a perspective view of an advertising sign showing my new design. Fig. 2 is an end elevation thereof.

I claim:

The ornamental design for an advertising sign, as shown.

In witness whereof, I hereunto affix my signature this 7 day of January, 1926.

DOUGLAS S. CAMPBELL.
